INVENTOR -

A. N. Somers,
By his attorney, Charles D. Godding.

UNITED STATES PATENT OFFICE.

AMOS N. SOMERS, OF SHARON, MASSACHUSETTS.

AUTOMATIC MIXER AND DISTRIBUTER.

No. 811,749.

Specification of Letters Patent.

Patented Feb. 6, 1906.

Application filed July 7, 1905. Serial No. 268,691.

To all whom it may concern:

Be it known that I, AMOS N. SOMERS, a citizen of the United States, residing at Sharon, in the county of Norfolk and State of Massachusetts, have invented new and useful Improvements in Automatic Mixers and Distributers, of which the following is a specification.

This invention relates to a device for automatically mixing and distributing with accuracy chemical solutions and mixtures that are applied in the arts and industries as washes, sprays, and powders.

It is designed for use in the administration of medicines, disinfectants, insecticides, fungicides, and chemical fertilizers, said device acting automatically and with mathematical accuracy to overcome all the former difficulties in the uses hereinbefore set forth to which it is adapted and also eliminate all that is unsafe, unpleasant, and uncertain in said uses. Said device is used by physicians and dentists in the administration of medicine and in the application of disinfectants and is also adapted for use by all persons having the care of homes, hospitals, public buildings, factories, school-houses, warehouses, and stables in applying disinfectants and by farmers, gardeners, florists, and fruit-growers in spraying their crops to protect them from the ravages of insects and diseases. It is also well adapted for use by owners of forest, shade, and fruit trees and shrubbery in protecting them from the insects and diseases by which they are at present largely destroyed.

The object of the invention is to provide a device which will perform the functions hereinbefore set forth and which is simple in construction and operation and which is also cheap in construction, so that it may bring the same within the use and within the means of a large number of people.

The advantages of said device consist in the fact that it saves time, labor, and expense, while securing the best possible results in its accurate mixing and distributing of materials, such as hereinbefore set forth, with water or other liquids.

The invention consists in the combination and arrangement of parts set forth in the following specification, and particularly pointed out in the claims thereof.

Referring to the drawings, Figure 1 is a central vertical section, partly in elevation, of my improved mixer and distributer, partly broken away to save space in the drawings.

Fig. 2 is a detail plan of the main-passage-regulating stop-cock, showing the same in connection with the tubular main passage, said tube being partly broken away. Fig. 3 is a section, partly in elevation, taken on line 3 3 of Fig. 1 looking toward the right in said figure. Fig. 4 is a horizontal section taken on line 4 4 of Fig. 1 looking downwardly in said figure. 65

Like numerals refer to like parts throughout the several views of the drawings.

In the drawings, 5 is the top, and 6 the base, of my improved mixing and distributing device. The base 6 consists of a receptacle provided with a cylindrical chamber 7 in the interior thereof. The top 5 comprises a tube 8, which forms a handle and has extending therethrough a main passage 9, said tube being provided with an inlet-orifice 10 and an outlet-orifice 11. The inlet end of said tube is screw-threaded interiorly at 12, while the outlet end thereof is screw-threaded exteriorly at 13. Between the inlet and outlet orifices, as will be seen, the tube 8 extends transversely across the receptacle or base 6, and an opening 14, located beneath said tube, extends across the top 5, so that the central portion of said tube may be used as a handle, whereby the device as a whole may be conveniently carried. 85

An inlet-passage 15 extends from the interior of the tube 8, adjacent to the inlet end thereof, downwardly through the top 5 and terminates in the chamber 7. A tube 16 is connected at the upper end thereof to the top 5 at the bottom of the inlet-passage 15 and projects downwardly therefrom toward the bottom of the chamber 7, and at its lower end is bent in a curve, as will be observed in Fig. 4, extending partly around said chamber, the lower free end 17 of said tube 16 being curved upwardly, so that any liquid or compressed air forced through the passage 15 and tube 16 will be directed around the interior of the chamber and also upwardly therein to thoroughly mix the contents in said chamber, as hereinbefore described, and to drive said contents outwardly from said chamber through the outlet-passage 18, which extends upwardly from the chamber 7 through the top 5 and terminates at its upper end in a tube 19. The tube 19 is bent or curved at its upper free end and terminates adjacent to the outlet-orifice 11 and preferably concentric with the main passage 9. 105

A stop-cock 20 is located in the main pas-

2

sage 9 between the inlet-passage 15 and the outlet-passage 18, said stop-cock being provided with a handle 21 and having fast thereto an index-finger 22, so arranged as to pass over the graduations 23 provided upon the flat annular surface 24, formed upon the upper side of the tubular handle 8. The graduations 23 are subdivisions of a quarter-circle, and when in the position indicated in Figs. 1 and 2 the index shows that the stop-cock is wide open, the index then pointing to the graduation marked "100," and when the stop-cock is closed the index will point to the graduation marked "0," so that said graduations enable the operator to tell to a nicety just how much the stop-cock is open and at what angle said stop-cock stands with relation to the median central line of the main passage 9.

20 The inlet-passage 15 is provided with a stop-cock 25 and the outlet-passage 18 with a stop-cock 26, each of said stop-cocks being provided with an index-finger 27 and 28, respectively, as shown in dotted lines, Fig. 1, said index-fingers traveling over graduated indices or scales 29 and 30, respectively, whereby the amount of opening of each of said stop-cocks is readily determined by the operator.

30 A screw-plug 31 is provided in the top 5, whereby ready access may be obtained to the interior of the base or receptacle 6 for the purpose of inserting any desired material, either liquid or solid, in the interior of said receptacle or in the chamber 7.

35 The operation of my improved mixer and distributor is as follows: Assuming that the material is in powdered form and that it is desired to mix the same with a liquid—such as, for instance, water—said material is inserted in the chamber 7 by removing the screw-plug 31, and said screw-plug is then screwed tightly in place. The tube 8 is connected at its inlet end by a hose or pipe to the water-supply. The water is then turned on and allowed to flow through the passage 9 and out at the outlet-orifice 11, a portion of the water (depending upon the position of the stop-cock 20 and of the stop-cocks 25 and 26) 45 passing through the inlet-passage 15 and inlet-tube 16, out of the open end 17 of said tube, and mixing with the powder, which is thoroughly stirred by the force of the water and dissolved in said water, which then passes outwardly from said chamber 7 through the outlet-passage 18 and out of the tube 19, where it is again mixed with the water which is passing through the main passage 9. It will be seen that by turning the different stop-cocks to different positions a different amount of material may be mixed with the water and different results obtained both as to the amount of material mixed with the water and also as to the force with which 55 said water and the material which is mixed

therewith are ejected from the tube 8, so that a very strong solution may be obtained or a very weak solution, and any desired strength of solution from the strongest to the weakest by proper manipulation of the different stop-cocks.

If desired, it is evident that the stop-cocks 25 and 26 may be closed and the device used without intermixing with the water any of the material contained in the chamber 7, or, if desired, the stop-cock 20 may be closed and compressed air forced through the inlet-passage 15 into the chamber 7 and the powdered material contained therein forced out through the outlet-passage 18.

Having thus described my invention, what I claim, and desire by Letters Patent to secure, is—

1. A device of the character described comprising in its construction a receptacle having a chamber therein, said device provided with a main passage outside said chamber, said main passage having an inlet and an outlet orifice, said device provided with an inlet-passage leading from said main passage at the inlet end thereof to said chamber, a tube connected to said inlet-passage and projecting therefrom downwardly toward the bottom of said chamber, said device provided with an outlet-passage leading from said chamber into the outlet end of said main passage, a stop-cock located in said main passage between the points where said inlet and outlet passages connect with said main passage, graduations whereby the angular location of said stop-cock relatively to the median line of said main passage is indicated, a stop-cock located in each of said inlet and outlet passages, respectively, and graduations whereby the extent of opening of said last-named stop-cocks is indicated.

2. A device of the character described comprising in its construction a receptacle having a chamber therein, said device provided with a main passage outside said chamber, said main passage having an inlet and an outlet orifice, said device provided with an inlet-passage leading from said main passage at the inlet end thereof to said chamber, a tube connected to said inlet-passage and projecting therefrom downwardly toward the bottom of said chamber, said device provided with an outlet-passage leading from said chamber into the outlet end of said main passage, a stop-cock located in said main passage between said inlet and outlet passages, and a stop-cock located in each of said inlet and outlet passages, respectively.

3. A device of the character described comprising in its construction a receptacle having a chamber therein, said device provided with a main passage outside said chamber, said main passage having an inlet and an outlet orifice, said device provided with an inlet-passage leading from said main passage at the

inlet end thereof to said chamber, a tube connected to said inlet-passage and projecting therefrom downwardly toward the bottom of said chamber and curved at its lower end to 5 extend partly around said chamber, said device provided with an outlet-passage leading from said chamber into the outlet end of said main passage, a stop-cock located in said main passage between said inlet and outlet 10 passages, and a stop-cock located in each of said inlet and outlet passages, respectively.

4. A device of the character described comprising in its construction a receptacle having a chamber therein, said device provided 15 with a main passage outside said chamber, said main passage having an inlet and an outlet orifice, said device provided with an inlet-passage leading from said main passage at the inlet end thereof to said chamber, a tube connected to said inlet-passage and projecting downwardly therefrom toward the bottom of 20 said chamber and curved at its lower end to extend partly around said chamber, said device provided with an outlet-passage leading 25 from said chamber into the outlet end of said main passage, a tube leading from said outlet-passage into said main passage at its outlet end, bent at the free end thereof, and ter-

minating concentric with said main passage adjacent to the outlet-orifice thereof. 30

5. A device of the character described comprising in its construction a top and a base, detachably fastened together, said base comprising in its construction a receptacle having a chamber therein, said top comprising in 35 its construction a tubular handle extending transversely across said receptacle and terminating at its opposite ends in an inlet and an outlet orifice, respectively, with screw-threaded projections thereon, a stop-cock in 40 said tubular handle between said orifices, said top provided with an inlet-passage extending from the interior of said tube adjacent to said inlet-orifice to the interior of said receptacle and with an outlet-passage leading 45 from the interior of said receptacle to the interior of said tube adjacent to said outlet-orifice, and a stop-cock located in each of said inlet and outlet passages, respectively.

In testimony whereof I have hereunto set 50 my hand in presence of two subscribing witnesses.
